UNITED STATES PATENT OFFICE.

NATHANIEL DAVIS, OF MONTPELIER, VERMONT, ASSIGNOR OF ONE-HALF
TO GEORGE L. DAVIS, OF NORTH ANDOVER, MASSACHUSETTS.

REFRIGERATOR.

SPECIFICATION forming part of Letters Patent No. 399,976, dated March 19, 1889.

Application filed August 13, 1888. Serial No. 282,565. (No model.)

To all whom it may concern.

Be it known that I, NATHANIEL DAVIS, of Montpelier, county of Washington, State of Vermont, have invented an Improvement in 5 Refrigerators, of which the following description, in connection with the accompanying drawings, is a specification, like letters and figures on the drawings representing like parts.

This invention has for its object to provide 10 a refrigerator of novel construction especially adapted for use in warm climates, where ice is expensive, my improved refrigerator effecting a very considerable saving in the consumption of ice.

15 The particular features of my invention will be pointed out in the claims at the end of this specification.

Figure 1 is a side elevation of a refrigerator embodying my invention, the doors to the 20 food chambers or compartments being open; Fig. 2, a horizontal section of the refrigerator shown in Fig. 1 on line $x\ x$; Fig. 3, a vertical section of the refrigerator on line $x'\ x'$; Fig. 2; Fig. 4, a vertical section of the refrigerator on line $y\ y$, Fig. 3, and Fig. 5 a detail to be referred to.

The body of the refrigerator, composed of an outer wall or casing, a , an inner wall, a' , of wood or other material, is supported upon 30 suitable legs, a'' , the top and front side of the refrigerator being shown as provided with doors.

The outer and inner walls are separated by an air space or chamber which is subdivided, 35 in accordance with my invention, into a number of chambers, a^2 , by partitions a^3 , preferably of air and water proof non-heat-conducting material, such as paper-board coated with paraffine or other oleaginous material.

40 The partitions a^3 are maintained at the proper distance apart by cleats or strips, as a^5 , of wood or other suitable material, the said cleats or strips a^5 being of such thickness and so arranged as to leave the chambers a^2 of substantially the same width, as shown in Fig. 2. The partitions a^3 , being of a non-heat-conducting material, effectually prevent the outside heat from penetrating into the interior of the refrigerator.

45 The refrigerator at its interior is provided,

as shown, with a horizontal dividing-wall, b , forming below it a food-receiving compartment or chamber, b' , and the space above the said wall is divided by a vertical wall, b^2 , into chambers $b^3\ b^4$, the chamber b^4 being provided, 55 as shown, with a false or auxiliary bottom, b^5 , upon which is placed the ice, the said auxiliary bottom being supported above the wall b , so as to leave a cold-air passage, b , under the said auxiliary bottom. The compartment b^3 60 communicates with the compartment b' by a passage or port, c , (see Figs. 2 and 3,) formed, as shown, by cutting a slot through the horizontal partition b , the said port or passage being controlled from within the chamber b^3 65 by a valve, c' , hinged, as at c^2 , to the said wall b , the said valve being closed when the door c^3 is open by a spring, c^4 . The port c is also controlled from within the chamber b' by a second valve, c^5 , made as a slide-valve. 70 The compartment b^4 communicates with the compartment b' by passage or port b^6 , (see Fig. 3,) controlled by valve 3, pivoted at 4 in portions of the wall b , the said valve 3 being connected by a rod, c^6 , to the valve c^5 , before 75 described, and in practice supported in suitable ways or cleats, $t\ t$, the said rod being provided, as shown, with a cam or projection, c^7 , which is acted upon by a cam or projection, c^8 , on the door c^3 of the compartment b' , to 80 open the said ports when the said door is closed, thus enabling the cold air to at such time descend into the compartment b' . The compartment b^3 communicates with the ice-receiving compartment b^4 by ports or passages 85 2, b^7 , and 7, the ports b^7 and 7 being formed, as shown, by slots at the top and bottom of the vertical partition-wall b^2 . The said ports b^7 and 7 are controlled by valves b^8 and b^9 , sliding in suitable ways next one side 90 of the partition b^2 , the said valves being connected by rods 10 and 12 to a pivoted lever, 13, (see Fig. 4,) the rod 10 having a cam projection, 15. The valves b^8 and b^9 are moved to uncover the ports by a cam or projection, 95 16, on the door c^3 , acting on the cam 15 on the rod 10, the said valves $b^8\ b^9$ being open when the door is closed, and closed by a spring, 17, when the door is open.

The doors of the refrigerator are provided 100

with double walls, and the space between the same is divided into chambers by partitions the same as the main walls of the body of the refrigerator.

5 In practice the ice is placed in the compartment b^4 , it resting on the auxiliary bottom b^5 . When all the doors are closed, communication is established between all the compartments, all the valves being turned to open all 10 the ports between the compartments except port 2, which is closed by the valve 3.

In some instances it may be desired to utilize only the upper half of the refrigerator, and in this case the door c^9 of the compartment b' may be left open, or the same may be closed, and the cam or projection 22 on the said door rendered inoperative—as, for instance, it may be hinged to the door and dropped or turned down, so as not to engage 20 the cam c^7 .

With the cam c^8 rendered inoperative, the rod c^6 is moved, as herein shown, by a spring, 20, connected to the rod c^6 and the wall b , to operate the valves and close the ports b^6 and 25 c , thereby cutting off communication between the upper and lower compartments, the valves being at such time in the position shown in Fig. 3.

The circulation of air may be entirely cut 30 off and the cold air confined in the ice-compartment b^4 , which may be effected, as herein shown, by opening both doors. This may be effected when it is desired to cleanse the compartments.

35 I have herein shown the valves controlling the ports or passages as automatically operated by the doors; but, if desired, they may

be individually operated by hand. The cover of the ice-chamber will be in whole or part removable for reception of ice.

I claim—

1. In a refrigerator, the body and a division-wall, b , to form ice and food compartments within said body, the auxiliary bottom b^5 in said ice-compartment, and passages or ports 45 c b^6 to establish communication between said compartments, combined with valves c^5 and 3, to control said ports or passages, respectively, said valves being connected by the spring-controlled sliding rod c^6 , having the 50 projection c^7 thereon, to be acted on by the cam c^8 of the food-compartment door to open said passages when the door is closed, substantially as and for the purpose specified.

2. In a refrigerator, the body division-walls 55 b b^2 , forming chambers b' b^3 b^4 , and having formed therein ports or passages to establish communication between said chambers b^3 b^4 for the cold air, combined with valves b^8 b^9 , to control the ports or passages 7 and b^7 , said 60 valves being connected by rods 10 12 and pivoted lever 13, and the projection 15 on said rod 10, and the cam 16 on the door of the chamber b^3 , to co-operate therewith, whereby the said valves are opened when the door 65 is shut, substantially as described.

In testimony whereof I have signed my name to this specification in the presence of two subscribing witnesses.

NATHANIEL DAVIS.
